UNITED STATES PATENT OFFICE.

CARLTON F. MUNCEY, OF WATERLOO, IOWA.

WRENCH.

Application filed April 30, 1924. Serial No. 710,127.

To all whom it may concern:

Be it known that I, CARLTON F. MUNCEY, a citizen of the United States, residing at Waterloo, in the county of Black Hawk and 5 State of Iowa, have invented new and useful Improvements in Wrenches, of which the following is a specification.

This invention relates to wrenches of the adjustable type.

10 A primary object of the invention is to provide a wrench which will be self adjustable upon its application to a nut or other object.

Another object is to provide a wrench having adjustable slideable spring pressed jaw plates having rods extending therefrom and movably associated within alternately arranged bores formed in the wrench body, whereby each plate is movable without interference from its companion plate, and permits the employment of a larger number of plates in a given area than ordinarily possible without unnecessarily weakening the body member, as it will be obvious in the 20 ordinary construction where the same number of plates are employed, the bores would necessarily have to be much closer to each other which would physically weaken the wrench as will be readily apparent.

30 This invention also consists in certain other features of construction and in the combination and arrangement of the several parts, to be hereinafter fully described, illustrated in the accompanying drawings and specifically pointed out in the appended claim.

35 In describing my invention in detail, reference will be had to the accompanying drawings wherein like characters denote like or corresponding parts throughout the several views, and in which:

In the drawings:—

Figure 1 is a top plan view of the wrench embodying the invention.

Figure 2 is a side elevation.

40 Figure 3 is a plan view with portions broken away to illustrate the interior construction.

Figure 4 is a sectional view taken on line 4—4 of Figure 3.

45 Figure 5 is a detail view of one of the adjustable jaw plates.

Figure 6 is a sectional view taken on line 6—6 of Figure 5.

50 Referring to the drawings in detail, the reference numeral 1 indicates the handle of the wrench which tapers from the stationary

jaws 2 and 3. The handle from the inner terminal of the jaws is provided with a recess 3' and from the inner wall of the recess a plurality of bores 4 are formed which terminate at a point midway the ends thereof. The bores 4 slidably receive the inner extremities of the rods 5 which will be presently described.

55 Arranged between the jaws 2 and 3 are a plurality of plates 6 slotted longitudinally adjacent the inner ends thereof as at 5' and each being further provided with a recess 6' longitudinally formed adjacent one side wall thereof, as clearly disclosed in Figure 5 of the drawings.

Surrounding the rods 5 and arranged within the recess of the handle are coil springs 7 having their inner convolutions 75 engaging the rear wall of the recess adjacent the marginal edge of the bores 4, the inner wall of the other recess 3' providing a contacting shoulder 7 therefor. The rods 5 projecting from the inner ends of the jaw plates 6 and as will be readily apparent the jaw plates are capable of rearward movement but the springs tend to urge them to their outermost position as clearly shown in Figures 1 and 3 of the drawings.

60 It should be noted that the bores 4 are alternately arranged as disclosed in Figure 4, so that the springs may have adequate space for movement thereof and the recess 6' of the plates are provided to receive the springs when the plates are in operative 90 position and by this construction it is obvious that each plate is movable without interference from its companion plate.

65 A kerfed headed bolt 8 passes through the jaws 2 and 3 and receives the jaw plates through the medium of the slots formed therein. This bolt not only strengthens the structure but prevents lateral displacement of the jaw plates.

70 The operation of the invention may be briefly described as follows:

The wrench is applied to a nut of less size than the space between the jaws 2 and 3, some of the jaw plates 6 coming in contact with the nut will move rearwardly against the tension of the springs 7, to move the rods in the bores 4, until the outer end of the slots come in contact with the bolt 8 and the plates, not engaged by the nut will remain in normal position with the adjacent plates in engagement with the sides of the nut to allow the maximum amount of 105 110

strength thereof to be exercised thereupon. Therefore, it will be apparent that this wrench is automatic in adjusting itself to the size of the nut or object to which it is applied.

It is thought from the foregoing description that the advantages and novel features of my invention will be readily apparent.

I desire it to be understood that I may 10 make changes in the construction and in the combination and arrangement of the several parts, provided that such changes fall within the scope of the appended claim.

Having thus described my invention, what 15 I claim as new is:—

A wrench of the character described comprising a handle, spaced stationary jaws formed thereon, said handle being recessed from the inner ends of the jaw and from the

20 inner end of the recess is provided with

alternately arranged bores, jaw plates normally arranged in contacting engagement between the jaws, and provided with longitudinally disposed slots, a rod inwardly extending from each jaw plate and each rod 25 having its free end mounted for slidable movement in the adjacent bore, springs surrounding the rods and engaging the inner end of the recess and adapted to force the plates to normal position, a bolt rigidly secured between the fixed jaw and passing through the slots provided in the jaw plates, constituting guiding means for said jaw plates and said jaw plates being provided with grooves to accommodate the outer ends 30 of the spring when the jaw plates are moved to operative position.

In testimony whereof I affix my signature.

CARLTON F. MUNCEY.
